UNITED STATES PATENT OFFICE.

JACOB LOUIS BAUER AND ROBERT BAUER, OF MILWAUKEE, WISCONSIN.

FOOD-COMMINUTING DEVICE.

1,324,778.

Specification of Letters Patent. Patented Dec. 16, 1919.

Application filed March 25, 1919. Serial No. 284,945.

To all whom it may concern:

Be it known that we, JACOB L. BAUER and ROBERT BAUER, citizens of the United States, and residents of Milwaukee, in the county of 5 Milwaukee and State of Wisconsin, have invented certain new and useful Improvements in Food-Comminuting Devices; and we do hereby declare the following is a full, clear, and exact description thereof.

10 Our invention relates to new and useful improvements in machines for shredding or comminuting food materials, and more particularly of that small type adapted for household use.

15 It is in general the object of our invention to simplify and otherwise improve the structure and increase the efficiency of devices of this character, as well as to increase the convenience of operation of such devices, and 20 the ease with which they may be assembled incidental to the frequent cleaning operations necessary in their continued use.

25 A further object resides in the provision of a machine of simple and compact assembly, wherein rotary motion of a suitable handle member is transformed into reciprocating motion of a cutting or shredding member, and whereby free discharge of material from the cutting or shredding member 30 is permitted.

35 A further object resides in the provision of improved and simplified manually operative means for feeding the work material to the cutting or shredding member of the device. A still further object resides in the provision of an arrangement, in a structure compassing the foregoing objects, wherein cutting or shredding members of different types may be readily substituted, to adapt 40 the machine for different desired operations.

With the above and other objects and advantages in view, which will be apparent as the description proceeds, our invention resides in the novel features of construction, 45 combination and arrangement of parts, as hereinafter more particularly described and defined by the appended claims.

In the accompanying drawings:

Figure 1 is a vertical sectional view 50 through a food comminuting machine embodying our invention, the plan of this section being indicated in general by the line 1-1 of Fig. 2.

Fig. 2 is a plan view of the machine, portions being broken away to more clearly show the structure.

Fig. 3 is a rear view of the upper portion of the machine.

Fig. 4 is an elevational view of a shredding member adapted for use in the ma- 60

chine. Referring now more particularly to the drawings, the embodiment of our invention therein shown is adapted to be mounted in the usual manner on the edge of a table or 65 other support, and to this end includes a standard 5 having its upper portion offset whereby to lie inwardly of the edge of the support, the lower portion of the standard carrying a support engaging jaw 6 and having 70 its lower extremity laterally directed for the reception of a clamp screw 7 whereby the standard may be firmly clamped to the table or other support. The upper end of the standard carries cross arms 8 having 75 bars 9 projecting horizontally from their outer ends and adapted to pass through the outstanding lugs 10 at the inner end of a feed cylinder 11 for the material to be 80 worked upon. The free end portions of the bars are shouldered to afford seats for the cylinder lugs, and wing nuts 12 are threaded 85 on the bearings to clamp the lugs against the shoulders whereby the cylinder may be firmly and rigidly mounted in a manner 90 which is, however, quickly detachable. The ends of the feed cylinder are entirely open, and a vertical wall 13 is carried by the inner end of the cylinder. Secured to this guide 95 wall at the sides of the cylinder opening are a pair of track ways each formed of a strip of metal 14 bent longitudinally to afford a channel shape therefor and having one side secured to the wall by rivets 15 passed therethrough and through a spacer strip 16 disposed in the channel.

The members for cutting, shredding or otherwise comminuting the work material are each in the form of a flat plate 17 having its edge portions engageable in the channels of the trackways whereby it is mounted for vertical reciprocating movement, and the cutting portions of the comminuting members are struck inwardly from the body of the plate, thus forming apertures in the plate through which the comminuted material passes. The cutting portions of the comminuting member may comprise shredding blades 18 extending transversely throughout the major portion of the width 110 of the plate in a preferably oblique direction, and as shown in Fig. 4, wherein the

communuting member is designated 17^a, the cutting portions may comprise a multiplicity of grater tongues 19.

For reciprocating the communuting member, a transverse plate 20 is mounted on the back of the member, in spaced relation thereto, by rivets 21, spacing sleeves 22 being disposed on the rivets between the communuting plate and said transverse plate.

10 This transverse plate is provided with a longitudinal slot 23 forming a track way in which is engaged a roller 24 mounted on pin 25 carried on the end of a crank arm 26 which extends from a shaft 27 journaled 15 in a bearing boss on the upper end standard 5, this crank being rotated between the support bars 9 of the feed cylinder. Outwardly of the boss 28, the shaft 27 is squared for the reception of a crank handle 29, which is retained in place by a wing nut 30 threaded on the end of the shaft.

Thus rotary motion of the crank handle 29 will be transformed in the vertical reciprocating motion of the communuting member, to effect its operation, it being noted that the operative stroke of the communuting member is preferably effected on the down stroke of the crank handle, to procure the most easy operation.

30 The upper portion of the feed cylinder 11 is apertured and enlarged to provide a supply hopper 31, and to feed the material in the cylinder toward the communuting member, a follower 32 is slideable therein, said 35 follower carrying a handle 33 which projects from the outer end of the cylinder. Movement of the follower from the outer end of the cylinder is normally prevented by stop lugs 34, and to permit this detaching 40 movement for the purpose of cleaning the device, the follow member is provided with peripheral slots 35 adapted to register with and receive the stop lugs.

In the operation of our device, food material to be worked upon is placed in the cylinder 11 through the hopper 31 thereof, the operator then grasps the crank handle 29 and the handle 33 of the follower and rotates the crank handle, simultaneously pressing the follower inwardly to feed the work material to the reciprocating communuting member. The comminuted material passes through the plate 17 and may be collected in any suitable receptacle disposed under 55 the inner end portion of the cylinder. When it is desired to clean the machine after operation, or to substitute a different type of communuting member, it is merely necessary to unscrew the wing nuts 12 and withdraw 60 the feed cylinder, the communuting member being then readily movable from its track-ways and the entire device being thus completely exposed to permit a convenient and thorough cleaning thereof, it being noted 65 particularly that the various parts of the de-

vice are so arranged as to avoid recesses or remote portions which would be difficult of cleaning.

While we have shown and described a preferred embodiment of our invention, it will 70 be appreciated that various changes and modifications of structure to meet differing conditions of use or manufacture may be employed without departing in any manner from the spirit of our invention, and that 75 various phases of our invention may be employed independently of the complete structure described, within the scope of the appended claims.

What is claimed is:

80 1. A device of the class described comprising a support, bars extending from the support and shouldered adjacent their outer ends, a feed chamber, lugs on the feed chamber detachably mounted on the outer ends of the bars, a communuting member movable between the support and the adjacent end of the feed chamber, and means for moving said communuting member.

85 2. A device of the class described comprising a support, bars extending from the support, a feed chamber detachably mounted on the bars, channel bars secured to one end of the chamber, spacer strips in said bars, a plate having its edge portion slidably engaged between the spacer strips and the outer sides of the channel bars, communuting portions struck inwardly from the plate, and means for reciprocating the plate.

90 3. A device of the class described comprising a support, bars extending from the support, a feed chamber detachably mounted on the bars, channel bars secured to one end of the chamber, spacer strips in said bars, a plate having its edge portion slidably engaged between the spacer strips and the outer sides of the channel bars, communuting portions struck inwardly from the plate, a slotted transverse track-plate carried by the first named plate in spaced relation thereto, 95 and a crank member carried by the support and engaged in the slot of said track-plate.

100 4. A device of the class described comprising a standard having means at its lower end for attachment to a support, a substantially horizontal feed chamber open at both ends and carried by the upper end portion of said standard in spaced relation thereto, and having an inlet in its upper portion intermediate of its ends, a reciprocative communuting member vertically movable between the standard and the adjacent end of the feed chamber, means carried by said standard for reciprocating said communuting member, and a follower member movable 105 into the chamber from its outer end portion.

110 5. A device of the class described comprising an upstanding support member, a substantially horizontal feed cylinder carried by the support in spaced relation thereto, an 115

- operating shaft journaled in said support and having its axis disposed approximately in alinement with the axis of the feed cylinder, a crank on said shaft between the support and feed cylinder, a comminuting member reciprocative at the adjacent end of the cylinder, and a connection between said reciprocative comminuting member and the crank.
- 10 6. A device of the class described comprising an upstanding support member, a substantially horizontal feed cylinder carried by the support in spaced relation thereto, an operating shaft journaled in said support, a crank on said shaft between the support and
- 5 feed chamber, a pin on the crank shaft extending toward the feed chamber, a comminuting member carried by the chamber and reciprocable across the end of the chamber, and means carried by the comminuting member for receiving the pin to procure reciprocation of the comminuting member, said feed chamber being readily detachable from the support.
- 15 In testimony that we claim the foregoing we have hereunto set our hands at Milwaukee, in the county of Milwaukee and State of Wisconsin.

JACOB LOUIS BAUER.
ROBERT BAUER.
